UNITED STATES PATENT OFFICE.

ERNEST L. GALE, OF YONKERS, NEW YORK, ASSIGNOR TO GURNEY ELEVATOR COMPANY, INC., A CORPORATION OF PENNSYLVANIA.

ELECTRICAL CONTROL SYSTEM OPERABLE AUTOMATICALLY TO LEVEL ELEVATORS WITH LANDINGS.

Application filed July 13, 1925. Serial No. 43,080.

My invention relates to elevators and more particularly to an electrical control system operable automatically to level an elevator with landings.

It is a well known fact that an elevator car will, after the hoisting operation is discontinued, coast through the mechanical brake, a greater distance with heavy load descending and light load ascending, than with heavy load ascending and light load descending. This varying coast of the car causes it to come to a stop either above or below the landing, and this fault is due to the automatic stopping apparatus now in common use wherein the adjustment to control the stopping operation is permanent and brings the car only with average load to a substantially level stop by coasting. Hence both time and power is wasted, more particularly when the car over-runs the landing, and this is so even with the use of automatic leveling devices now in common use, because of premature slowing down and very slow speed operation of the car through the leveling zone.

Hence, one of the objects of the present invention is to save both time and power by the provision of a load controlled stopping switch which varies automatically the point

wardly, or rather to raise its counterweight so that the same coasting condition is present with a light load descending as with a heavy load ascending; neither will coast as far as will a light load ascending or a heavy load descending. Since the car in coming to a gravity stop, moves at a uniformly decreasing rate, such stop is an ideal method and results in a substantial saving in time as compared with those leveling systems having a premature slow-down and a continued constant slow speed movement of the car through a leveling operation, the main purpose of which is to minimize the possibility of over-run.

On the other hand the load switch will for heavy load ascending and light load descending, continue the hoisting operation for a longer period of time than for a heavy load descending and a light load ascending, thereby bringing the car nearer to the landing and discontinuing the hoisting operation, so that under these load conditions which give rise to what may be termed the minimum coast, such coast will bring the car to a gravity stop without liability of over-run, such stop bringing the car substantially level with the landing.

In the operation of elevators it will be observed that heavy load descending and light load ascending are the conditions which give rise to maximum coast of the car and contribute more than any other factor to the over-run movement of the car, and since the timing operation as effected by the load stopping switch effects a gravity stop without liability of over-run, a very slow speed apparatus need not be employed and only a single hoisting motor as now commonly used for high speed elevators can be employed, which motor may operate the car at about a one hundred foot rate per minute, as slow speed.

The load controlled switch in its present embodiment, controls the car so that its coast brings it to a gravity stop within the bounds of what will be termed an exact leveling zone, this zone being necessarily very short and extending say only a few inches either side of a landing. When the car is in this zone, the hoisting operation is again continued

at which the hoisting operation is discontinued so that the varying coasts of the car due to varying load conditions will bring the car to a gravity stop substantially level with the landing without liability of over-running. Thus the load switch will, for heavy load descending and light load ascending, automatically discontinue the hoisting operation with respect to a pre-determined landing, and as to point of time, sooner, than for a light load descending and a heavy load ascending, thereby taking full advantage of those load conditions which cause the car to coast the maximum distance and the timing operation is such that the maximum coast will bring the car to a gravity stop substantially level with the landing without liability of over-run.

As it is customary in ordinary elevator installations to provide a counterweight which is equal to the weight of a car and one-half of the load which the car is arranged to carry, it follows that it takes a maximum amount of current to drive an empty car down-

under the control of leveling switches, and since the operation to level the car is of such short duration, the motor will not attain any appreciable speed. Furthermore, the leveling switches will operate automatically to maintain the car level with the landing during loading and unloading, under which conditions the car may tend to move from the landing due to change in length of the hoisting cables.

Other objects of the invention will appear hereinafter, the novel combinations of elements and arrangement of parts being pointed out in the appended claims.

Referring now to the drawings, Fig. 1, illustrates in a more or less diagrammatic manner, an electrical control system for elevators embodying the present load controlled automatic stopping switch; Fig. 2, illustrates an electrical control system for elevators embodying a load controlled automatic stopping switch of modified construction adapted for use with both A. C. and D. C. systems; Figs. 3, 4, and 5 illustrate different relative positions which the load stopping switch assumes for different load conditions, and Fig. 6, illustrates a load controlled stopping switch of modified construction.

Referring now to Fig. 1, the elements comprise an elevator car C which may be operated through any well known system of roping or gearing by a hoisting motor M provided with a usual electro-mechanical brake B in which the brake is applied by a spring 1, and is released by a brake magnet 2. A shunt field winding for the motor is designated 3, a starting resistance 4, and an accelerating magnet automatically to control the starting resistance is designated 5. Reversing switches for the motor M are designated R, R', and a feed circuit for reversing switch windings 6 and 7, is controlled by reversing switch relays T and T' provided with windings 8 and 9 respectively, and also by the load controlled stopping switch designated L. S., together with the electro-magnetic switches D and E. A car switch F in the present instance is of a type adapted for manual control by being provided with a usual hand lever 10, and which is also adapted for automatic actuation by being provided with a pair of bell-crank levers 11 each carrying a roller 13, said levers being connected by a pair of rods 13', fulcrumed at 14 which is eccentric to the center pivotal support of said car switch. The rollers 13 are adapted to co-act with a pair of leveling cams 15 and 16 positioned in the elevator hatchway, there being a pair of cams for each floor, only one floor being illustrated herein. This is more fully described in my copending application, Serial No. 635,764, filed April 30, 1923.

Coming now to the load controlled stopping switch L. S., it as a whole is carried on the elevator car, and comprises an arm 17

secured to which is a contact sector 18. A bell-crank lever 19, together with the arm 17, is mounted on a fixed pivotal support 20, said lever 19 carrying a contact 21, adapted to co-act with the contact sector 18, and a contact 22 to co-act with a fixed contact sector 23. The parts as shown are in a normal position. The arm 17 and its contact sector 18 are rocked a variable number of degrees by a current solenoid 24, against the action of a spring 25. In the present instance the desired operation of the contact sector 18 is obtained by utilizing the starting current of the armature of the hoisting motor as a measure of the load, and to obtain this result the current solenoid 24 is contained in the armature circuit. A holding-dog 26 is actuated by an electro-magnet 27 to engage a ratchet 28, and thereby hold said contact sector 18 at the highest point to which it has been moved at each operation of the motor from start. A spring 29 releases said dog from the ratchet when the said electro-magnet is de-energized. An electro-magnet 30 is adapted to actuate the bell-crank lever 19 in an anti-clock-wise direction and so rock the contact 21 in a path to co-act with the contact sector 18, and the contact 22 will likewise be rocked to co-act with the fixed contact sector 23. A bell-crank lever 31, carrying a roller 32, is operatively connected to the lever 19, and said lever 31 together with timing cams 33 serve to time the return movement of the contacts 21 and 22 to normal position by movement of the lever 19 in a clock-wise direction, said timing operation being directly in accordance with the movement of the car.

A complete cycle of operation will now be given; start of the car is initiated by moving the car switch handle in the desired direction, say for example to cause the car to ascend, in which case the segment 34 is moved to engage contacts 35, 35'. This simply closes a circuit for the winding 9 of the "up" reversing switch relay T', and the relay T' will now close its contacts. The contacts 36 associated therewith together with contacts 37 controlled by switch D, now close a feed circuit for the winding 7 of the up reversing switch R'. Said feed circuit may be traced as follows, from plus wire 38, contacts 37, wire 39, relay contacts 36, through up reversing switch winding 7 and thence to minus line by way of wire 41. The circuit for the relay winding 9 may be traced as follows, from plus wire, contact 35, to contact 35' by way of the segment 34, wire 42, through relay winding 9, and thence to the minus line by way of wire 43.

The up reversing switch R' will now close and direct current from any suitable source of supply designated plus and minus, through the motor armature in a manner to cause the car to ascend, the main circuits be-

ing well known and need not therefore be traced in detail. The reversing switch closes the brake winding circuit and the brake will thus be released. Assume now that the car 5 has what will be termed its maximum load. Under such load condition, the hoisting motor in starting to move the load in an ascending direction, will draw a relatively heavy current, and the current solenoid 24, being subjected to this relatively heavy current, will rock the contact sector 18 a maximum distance to its limit of movement as indicated in Fig. 5, against the action of the spring 25, and will be held in this position by the dog 10 26 actuated by the electro-magnet whose feed circuit 44 is now closed by the reversing switch R' from the plus main through the two upper right hand contacts of this reversing switch, wire 44 and solenoid 27, the other 15 terminal of which is connected to the minus main. When the car travels upwardly a few inches from the landing level through what will be termed the leveling zone, and which corresponds to the vertical portion 45 of the 20 cams 33, the roller 32 engages a rather sharp bevelled portion 46, thereby imparting a short rocking movement of the lever 19 to cause the contact 22 to co-act with the contact sector 23 and by so doing, close a self-holding 25 circuit for the up relay winding 9, and also close a circuit for the actuating winding 30 which will now rock the lever 19 in an anti-clock-wise direction to its limit of travel as indicated in Fig. 5, thereby rocking the contacts 21 and 22 in paths to co-act with the contact sectors 18 and 23 respectively. The self-holding circuit for the up relay winding 9 30 may be traced as follows, from plus wire 38, wires 47 and 48 to contact 22, sector 23, wires 49', 49, through knife switch 50 in the car, wire 51, back-contacts 52 on down relay T, wire 53, contacts 54, wire 55 forming a junction at 55' with wire 42, thence through winding 9 to minus line by way of wire 43. A 35 circuit for the actuating winding 30 may be traced as follows, the same as just traced up to and including the wire 49', thence from a junction 56, wire 57, contacts 58, wire 59, through winding 30, wires 60 and 61, through 40 up relay contacts 62, and thence to the minus line by way of wire 63. With the lever 19 now in actuated position, the roller 32 will be in an inoperative position so as to clear the timing cams at floors which the car passes by. Likewise, with the car switch in "on" 45 position, the rollers 13 are in an inoperative position so as to clear their respective leveling cams 15, 16 at floors which the car passes by.

The car now having moved a few inches 50 and thereby closing the self-holding circuit for the up relay winding 9, permits the car switch lever to be returned to "off" position, that is, assuming that a stop is desired at the next adjacent floor, and the car will continue its travel under automatic control.

With the car switch on "off" position at the present time, the control of the feed circuit just traced for the reversing switch winding 7 is transferred temporarily from the switch D to the switch E, the latter switch being 55 under control of the car switch in "off" position, in which position the segment 34, contacts with contacts 64, thereby closing a circuit for the winding 65 of switch E, and the winding 30 of the load stopping switch, said circuit being traced as follows, from wire designated plus, wire 66, through winding 65, wire 59, through winding 30, wires 69 and 61, contacts 62, and to the minus line by way of the wire 63. The switch E will now operate 60 and close a feed circuit for the reversing switch winding 7 as follows, from plus wire 38, wire 47, wire 67, contacts 68, and wire 69 to a junction 69' with the wire 39 and from there on as heretofore traced. Switch E will 65 also close contacts 70 which close a circuit for the winding 72 of the switch D, thereby causing the latter to open its contacts 37 and 58, and by so doing open at that point the feed circuit for the reversing switch winding 7 70 as initially traced, and also open at that point the circuit initially traced for the actuating winding 30. The switch D by closing its contacts 73, thereby closes a self-holding 75 circuit for the winding 72 which is maintained closed by the relay T', said circuit being traced as follows, from plus wire 38, wires 47 and 74, through winding 72, wire 75, contacts 73, wire 76 which forms a junction 76' with the wire 60 and from there on as 80 heretofore traced for the winding 30.

At this point in the operation, we now have the feed circuit as controlled by switch E, for the reversing switch winding 7, also the actuating winding 30 of the load controlled 85 stopping switch, under the control of the car switch in its "off" position, and when the ascending car reaches a zone which may be termed a "maximum coasting zone," so called 90 because it is measured by the maximum predetermined distance through which a maximum loaded car descending will by coasting come to a gravity stop substantially level with the landing, the car switch will be actuated automatically by the engagement of the roller 95 110 115 120 125 130 135 140 145 150 155 160 165 170 175 180 185 190 195 200 205 210 215 220 225 230 235 240 245 250 255 260 265 270 275 280 285 290 295 300 305 310 315 320 - of the load controlled stopping switch and the duration of contact between the contact 21 and its co-acting contact sector 18, depends on the degree of rocking movement of said sector as effected by the current solenoid 24, and this degree of movement as effected by utilizing the starting current taken by the armature of the hoisting motor as a means to measure the load, results in a greater rocking 5 movement of the contact sector for a heavy load ascending and a light load descending, than for a heavy load descending and a light load ascending. It will be observed that the automatic transfer of the control of the hoisting 10 operation from the centered car switch and switch E, to the load controlled stopping switch exclusively, is always effected at a pre-determined fixed point relative to any desired pre-determined landing, said point 15 being that at which the car is in position so that the roller 32 will engage the highest point 77 of the cam 33, and by making such provision, the stretch or contraction or rather twist or untwist of the hoisting cables as a 20 factor in causing over-run or under-run is over-come. Take now the heavy load ascending condition as assumed heretofore under which condition the current solenoid actuates the contact sector the maximum distance. 25
- 30 The parts will now assume a relative position as shown in Fig. 5, and the contact 21 and the contact sector 18 now exclusively control a feed circuit for the winding 7 of the up reversing switch R', and the self-holding circuit for the winding 9 of the relay T' is closed by way of the contact 22 and sector 23. Hence the hoisting operation will be continued under the control of the load stopping switch from the time roller 32 engages the high- 35
- 40 est point 77 of the cam 33, and until the contact 21 in its return movement to normal position as timed by the cam 33, rides over the full length of the sector 18, said contact 21 being rocked sufficiently by the cam 33 to dis- 45
- 50 engage said sector 18 when the car reaches what may be termed the minimum coasting zone, through which the car by its coast will bring it substantially level with the landing, or in effect, the zone designated "leveling 55 zone." The feed circuit as controlled for the winding of the reversing switch R' may be traced as follows, from plus wire 38, wires 47 and 48, wire 78, contact 21 to contact sector 18, wire 79, junction 79' formed with wire 39, contacts 36, through reversing switch winding 7, and thence to the minus line by way of wire 41. The self-holding circuit for the winding 9 of the relay T' is opened at the 60 contact 22, when the roller 32 rides down the sharp bevel 46, and the roller 32 will now engage the vertical face 45 of the cam, and the lever 19 is thereby returned to its normal position as shown, in which position thereof, the contact 21 will co-act with a fixed contact 65 80 to again close the feed circuit for the wind-

ing of the reversing switch R'. When the roller 32 initially engages the vertical face 45, the leveling roller 13 has still a few inches more of travel before engaging the incline portion of the cam 15, and in this manner the 70 car switch is automatically maintained in "on" position to maintain closed at that point the circuit for the winding of the relay T'. Hence for the exact leveling operation of the car, the control of the hoisting operation is 75 under the control of the car switch and the contacts 21 and 80. When the car reaches an exact level with the landing, the roller 13 engages the incline face of the cam 15, thereby permitting a centering spring 81, automatically to center the car switch. By centering the car switch, the relay winding 9 is de-energized and the relay contacts move to open position, thereby restoring the switch D to normal position as shown. The car switch 80 control of the reversing switch relays T and T', dominates over the self-holding circuit contacts for said relays, because as will be seen, the self-holding circuit for one, includes back-contacts controlled by the other. This 85 in effect means that the car can be reversed at any point outside of the cam zones, by car switch operation. 90

If at any time it may be desired to retain control of the hoisting operation solely by 95 means of the car switch, and to preclude operation of the load controlled stopping switch, this can be effected simply by opening the knife switch 50 in the car. This in effect puts the relays T and T' solely under the control of the car switch, and the feed circuit for the reversing switch windings will be by way of the contacts 37 in a manner hereinbefore traced. 100

It will be seen now that by the use of the load controlled stopping switch the car will for all load conditions be brought substantially level with the landing, or in other words within the bounds of the exact leveling zone, and this zone may extend only a few inches either side of the landing level, and hence the duration of contact necessary to effect the exact leveling is of such short duration that the motor will not attain any appreciable speed such as might cause an over-run movement. Reducing the leveling zone in a manner as affected by the load controlled stopping switch precludes any need for very slow speed operation, and thus the present day standard motor as used for high speed elevators can be used without the provision of any auxiliary means to effect a very slow speed movement of the car. 110 115 120

If during loading and unloading, the car platform should tend to move from a level with a landing by reason of the hoisting cables untwisting or twisting, the car switch will then be actuated automatically by the leveling cams 15 or 16 and associated parts connected to the car switch, to control the hoisting motor 125 130

to return the car to a level with the landing and automatically stop the car thereat, thereby maintaining in effect the car level with the landing during loading and unloading.

- 5 For the heavy load ascending condition, it has been shown that the contact sector 18 is actuated a maximum distance and when the transfer of the control of the hoisting operation is made at the point 77, the load controlled stopping switch then continues the hoisting operation to move the car through the maximum coasting zone, and when the car reaches the minimum coasting zone, the hoisting operation is automatically discontinued. 15 and the brake is applied, and under such load condition and direction of car travel, the car will coast a minimum distance and by so doing move within the bounds of the exact leveling zone.
- 20 With a light load ascending, the hoisting motor at starting will draw a current of comparatively small value, and the current solenoid being subjected to this current will not actuate the contact sector 18 against the action of the spring 25, and the contact sector 18 will remain in normal position as shown in Fig. 3, in which the contacts 21 and 22 are in actuated position. Hence it will be seen that under this load condition and direction of 25 car travel, when the transfer of the control of the hoisting motor is made at the point 77, the hoisting operation will not be continued at said point because the sector 18 has not been moved into position to be engaged by the contact 21 and hence the car will under such load condition and direction of car travel, coast its maximum distance through the maximum coasting zone, and in this way come to a gravity stop within the bounds of the exact leveling zone. Also, with a heavy load descending the car will coast its maximum distance, and the motor at starting will draw a current of comparatively 30 small value, hence for such load condition and direction of car travel, the contact sector will assume the position as illustrated in Fig. 3, thereby permitting the car to coast its maximum distance and come to a gravity stop substantially level with the landing without liability of over-running the 35 landing.

With a light load descending, the car will coast its minimum distance, and the motor at starting will draw a current of comparatively high value and for this load condition and direction of car travel, the contact sector will assume the position as illustrated in Fig. 5, in which case the load switch continues the hoisting operation in the same manner as described in connection with the heavy load ascending condition.

With average load condition and either direction of car travel the hoisting motor at starting will draw an appreciable current such as will energize the current solenoid to cause it to rock the contact sector about one-half of

its maximum distance as illustrated in Fig. 4, so that when the transfer of the control of the hoisting motor is made at the point 77, the load controlled stopping switch will continue the hoisting operation through about one-half the distance of the maximum coasting zone, and upon reaching such point the hoisting operation is automatically discontinued and the brake is applied by reason of the contact 21 disengaging the contact sector 18 and the car will then coast and come to a gravity stop within the bounds of the exact leveling zone.

Referring now to Fig. 2, the load is measured mechanically as for example by providing a spring suspension 90 for the car, and movement of the car as caused by loading and unloading is imparted to a pair of contact sectors 91 and 92, through the intermediary of a cam 93 fixed to the cable hitch-block, and a lever 95 secured to a pivoted lever 96 to which the sector 91 is attached, the lever 95 carrying a roller 97. The sector 92 is attached to a lever 98 which together with the lever 96 is supported for rocking movement on a fixed pivot 99, said levers rocking the contact sectors 91 and 92 in opposite directions as effected by a spring 99', when the roller 97 follows the incline cam face by moving downwardly as effected by compression of the supporting springs when a load is on the car platform. Any movement imparted to the lever 96 by the lever 95 to which it is attached, is also imparted to the lever 98 through the intermediary of a pair of links 100, connected at their upper ends to a sleeve 101, slidable on a fixed vertically disposed guide rod 102. The sector 91 controls a feed circuit for the up reversing switch winding 7, and additional contacts 103 are provided on the reversing switch relay T' which are included in said feed circuit. The sector 92 controls a feed circuit for the down reversing switch winding 6, and additional contacts 105 are provided on the reversing switch relay T which are included in said circuit. Thus it will be seen that the sector 91 independently controls the feed circuit for the up reversing switch winding and the sector 92 independently controls the feed circuit for the winding of the down reversing switch, and by providing the two independent contact sectors, the results obtained are identical with those just described in connection with the load switch illustrated in Fig. 1, in which the load is measured electrically, and since a detailed description would be merely repetition, it is deemed unnecessary.

The rocking lever 19 in this instance is provided with an additional arm 106 carrying a contact 21' to co-act with the contact sector 92, and together with the contact 21 is connected to the wire 78.

Assume now that a heavy load is put on the car. This will cause the car body to compress

the springs 90 and the downward movement as caused by the load will permit the spring 99 to actuate the lever 95 in accordance with the rocking movement of the roller in following 5 the incline face of the cam 93, and in this manner the two contact sectors 91 and 92 through the link connection will be rocked in opposite directions from the normal position as shown. Hence if the down relay T is closed, its contacts 105 render the sector 92 and its associated contact 21' operable to control the stopping operation, and for this load condition it will be seen that the sector 92 has been moved its maximum distance in a counter- 10 clock-wise direction in which position it is entirely overlapped by its associated contact 21' when the latter has been actuated by the actuating winding 30. On the other hand, if the up relay T' is closed, its contacts 103 15 render the sector 91 and its associated contact 21 operable to control the stopping operation, and for said heavy load condition, the sector 91 has been moved its maximum, so that its associated contact 21 will in its return move- 20 ment from actuated position, travel over the entire length of the sector 91, and in this manner continue the hoisting operation in a manner as hereinbefore described in connection with Fig. 1.

30 In Fig. 2, a two speed motor is illustrated, fast speed being obtained by operation of a fast and slow speed switch 106, which when actuated by an electro-magnet 107, introduces a resistance 108 in the circuit of the 35 shunt field winding 3. Usual fast speed contacts 109 are provided on the car switch to control the operation of the fast and slow speed switch 106. A self-holding circuit for the winding 107 is closed by way of contacts 111 controlled by the switch D, wire 110, contacts 112, wire 113, through winding 107, wire 114, through contacts 115 which are closed when the last arm on the accelerating magnet (not shown) operates and thence to the minus line by way of wire 116. 40 The transfer of this self-holding circuit to a switch G is effected by centering the car switch F after it has been operated to initiate the start of the car and effect its operation at fast speed, and by centering the car switch at this time the windings 117 (of switch G) and 30 are put under the control of the car switch in centered position. The feed circuit for the reversing switch windings 6 and 7 is initially closed by way of the contacts 37 on the switch D and is directed to the proper reversing switch winding by whichever relay T or T' is closed as effected by operation of the car switch. In this case 45 the range of movement of the contacts 21 and 21' is extended so that by actuation thereof by the winding 30 they will over-lap slightly their respective contact-sectors 91 and 92 with the sectors in normal position as shown, 50 and hence when the switch D operates due to the closing of switch G, the feed circuit for the reversing switch winding will then be controlled by the load switch contacts and the relay contacts 103 or 105. The stopping cam 33 is in this instance provided with 55 a raised vertical extension 127 at each end and the leveling cams 15 and 16 are elongated so that the ear switch will be actuated automatically when the rollers 13 engage their respective cams, to effect slow speed opera- 60 tion of the car and at the same time transfer the control of the slow speed operation of the car to the load stopping switch by opening the circuit of the windings 117 and 30 at the car switch contacts 64, such transfer and slow down being automatically effected by actuation of the car switch when the car is at such a point that the roller 32 will initially engage the high portion of the cam 33 at the point designated 127'. The slow speed 65 operation of the car will continue until the roller 32 rides down the rather sharp bevel 118 at which point the maximum coasting zone begins, the roller in following the sharp bevel permitting quick movement of the contacts 21 and 21' to a position from which they take up proper control of the stopping operation, and this quick movement will for example, move the contact 21 70 from its over-lapping position to disengage the contact sector 91, if, as when the car has only a very light load, the sectors remain in the position as shown. Hence from the time the car reaches the maximum coasting zone, the point at which the hoisting operation is 75 discontinued will be varied automatically by the load controlled switch in accordance with two factors, viz, the load on the car and the direction of car travel, the effect being to discontinue the hoisting operation sooner 80 for a heavy load descending and a light load ascending, than for a heavy load ascending and a light load descending.

85 In connection with Fig. 2 the method of obtaining fast speed operation has been described in detail and sufficient illustration is thought to be given in connection with the slow speed operation as will give a clear understanding of such operation since circuits not touched upon are identical with 90 those illustrated and described in detail in Fig. 1, and hence to illustrate and describe such in detail would be mere repetition.

95 In Fig. 6, the load controlled switch is of a modified construction adapted to measure the load electrically as in the construction illustrated in Fig. 1. In this construction the lever 119 carries a pivoted switch arm 120 having a roller 121 which by rocking movement of the lever as by energizing the 100 winding 30, initially closes contacts due to the roller 121 engaging a fixed cam 123, and an additional cam 124 carried by a pivoted arm 125 is rocked a variable number of degrees by energization of the current solenoid 105

in a path to be engaged by the roller 121 and by so doing impart a further rocking movement to the switch lever to close contacts. The two cams 123 and 124 are off-set 5 from each other and the roller 121 is of sufficient width to be engageable by both. The contacts 126 correspond to the contact sector 18 and the contact 21 as to function and as will be obvious the cam 124 through its 10 variable range of movement, varies the time period through which the contacts will be maintained closed as when the lever 119 is moving to its return or normal position as illustrated, and the contacts 122 as to function 15 correspond to the sector 23 and the contact 22 in Fig. 1.

It will be pointed out in connection with the load controlled switch as embodied herein that it is not dependent for its adjustment on 20 the stretch or contraction of the hoisting cables and because of the fact that as herein provided, the timing of the control of the hoisting operation by the load controlled stopping switch is always effected at a pre-determined fixed point relative to any pre-determined landing, thereby eliminates stretch and contraction of the hoisting cables as a factor or as a contributing cause for the car over-running or under-running the desired landing. Hence the other predominating factor which gives rise to over-run and under-run which factor is the variable coast due to varying load conditions is successfully taken care of by the present invention in such 30 a manner that the car under any condition of loading will coast to a gravity stop substantially level with the landing without liability of over-running. Over-running as compared with under-running involves greater loss of 40 time, and the oscillation of the car to level it is discomforting to the passengers, wasteful of power, and deteriorative to the hoisting apparatus.

Having thus described the invention and 45 without limiting myself to the precise details of construction of arrangements of parts, what I claim as new and desire to protect by Letters Patent of the United States is:

1. In an elevator system, the combination 50 with the car, a hoisting motor, and means operable solely in accordance with the load as measured by the current in the armature of said motor, to discontinue the hoisting operation of said motor with respect to a pre-determined 55 stopping point, sooner for a heavy load descending and a light load ascending, than for a heavy load ascending and a light load descending.

2. In an elevator system, the combination 60 with the car, a hoisting motor, manually controlled means and means on the car operable in accordance with the load and independently of the stretch and contraction of the hoisting cable, to discontinue the hoisting

operation with respect to a stopping point 65 predetermined by actuation of the manually controlled means, sooner for a heavy load descending and a light load ascending, than for a light load descending and a heavy load ascending, so that the car by its coast will 70 come to a gravity stop substantially level with the landing.

3. In an elevator system, the combination with the car, a hoisting motor, and a circuit controller for the motor having a timing 75 movement only during movement of the car through a maximum coasting zone at a pre-determined landing.

4. In an elevator system, the combination with the car, a hoisting motor, a circuit controller for the motor having a timing movement only during movement of the car in either direction through a maximum coasting zone, and means to open-circuit said circuit controller to discontinue the hoisting operation of said motor at different points within the bounds of said coasting zone, depending on the load and direction of car travel, so that the coast of the car will bring it to a gravity stop substantially level with a landing. 80 85 90

5. In an elevator system, the combination with the car, a hoisting motor, a circuit-controller to control the operation of said motor, means to impart a timing movement to said circuit controller directly in accordance with the movement of the car, and means to open-circuit said circuit controller, dependent on the load and direction of car travel, at any point within range of its timing movement. 95

6. In an elevator system, the combination with the car, a hoisting motor, a stopping switch adjusted automatically in accordance with the load, to vary the point at which the hoisting operation is discontinued so that the car by coasting will come to a gravity stop 100 substantially level with a pre-determined stopping point, and means to time the operation of the stopping switch only during travel of the car in either direction through a pre-determined zone related to a pre-determined 105 stopping point. 110

7. In an elevator system, the combination with the car, a hoisting motor, a stopping switch, means to time the operation of the stopping switch to discontinue the hoisting operation of said motor only during travel of the car in either direction through a maximum coasting zone, and means controlled automatically by the load to vary within the bounds of said zone, the point at which said stopping switch is open-circuited to discontinue the hoisting operation so that the car by coasting will come to a gravity stop substantially level with a landing. 115 120

8. In an elevator system, the combination with the car, a hoisting motor, a stopping switch, means to time the operation of said switch, means to render said timing operation 125

effective always at a pre-determined fixed point relative to any pre-determined stopping point regardless of stretch or contraction of the hoisting cables, and means controlled automatically by the load to vary within the range of said fixed point and said pre-determined stopping point, the point at which said stopping switch is open circuited so that the car by its coast in either direction will come to a gravity stop substantially level with said stopping point without liability of over-running said point regardless of the capacity of the load.

9. In an elevator system, the combination with the car, a hoisting motor, a stopping switch, means to initiate the start of the car, means to transfer the control of the hoisting operation exclusively to the said stopping switch always at a pre-determined fixed point relative to any pre-determined stopping point, and means controlled automatically by the load to vary within the range of said fixed point and said pre-determined stopping point, the point at which said stopping switch is open-circuited so that the car regardless of the capacity of its load will by coasting, come to a gravity stop substantially level with said stopping point without liability of over-running said point.

10. In an elevator system, the combination with the car, a hoisting motor, a stopping switch, means to initiate the start of the car, means to transfer the control of the hoisting operation exclusively to said stopping switch always at a pre-determined fixed point relative to any pre-determined stopping point, means automatically to time the operation of said switch rendered effective only when the car reaches said fixed point, and means controlled automatically by the load to vary within the bounds of said points, the point at which the hoisting operation is discontinued, said hoisting operation being discontinued sooner for a heavy load descending and a light load ascending, than for a heavy load ascending and a light load descending.

11. In an elevator system, the combination with the car, a hoisting motor, a stopping switch, means to initiate the start of the car, means independent of said initiating means automatically to control the hoisting operation to continue movement of the car, means operable automatically to transfer the control of the hoisting operation exclusively to said stopping switch always at a pre-determined fixed point relative to any pre-determined stopping point, and means controlled automatically by the load to vary within the bounds of said points, the point at which said stopping switch is open-circuited, so that the hoisting operation is discontinued sooner for a heavy load descending and a light load ascending than for a heavy load ascending and a light load descending and the car by coasting under these conditions will come to a

gravity stop substantially level with the stopping point without liability of over-running.

12. In an elevator system, the combination with the car, a hoisting motor, a car switch to initiate the start of the car, means operable by centering the car switch automatically to continue the movement of the car, and a stopping switch controlled automatically by the load and rendered operable to control the hoisting operation always at a pre-determined fixed point relative to a predetermined landing.

13. In an elevator system, the combination with the car, a hoisting motor, a car switch to initiate the start of the car, a stopping switch controlled automatically by the load to vary the point at which the hoisting operation is discontinued, and means to time the operation of said stopping switch rendered effective always at a pre-determined fixed point relative to a pre-determined landing.

14. In an elevator system, the combination with the car, a hoisting motor, means to initiate start of the car, a stopping switch controlled automatically by the load to vary the point at which the hoisting operation is discontinued so that the car by coasting will come to a gravity stop substantially level with a landing, and means operable automatically to bring the car to an exact level with the landing if subsequently to its coast and by its coast the car does not come to a stop at an exact level with the landing.

15. In an elevator system, the combination with the car, a hoisting motor, a car switch to control the hoisting operation, a stopping switch controlled automatically by the load to vary the point at which the hoisting operation is discontinued, so that the car by coasting will come to a gravity stop substantially level with a landing, and means automatically to actuate said car switch to exactly level the car.

16. In an elevator system, the combination with the car, a hoisting motor, a load controlled stopping switch, and means automatically to time the operation of said switch during movement of the car in either direction only in a pre-determined zone related to a pre-determined landing.

17. In an elevator system, the combination with the car, a hoisting motor, a load controlled stopping switch, and means automatically to time the operation of said switch during movement of the car in either direction only in a pre-determined maximum coasting zone related to a pre-determined landing.

18. In an elevator system, the combination with the car, a hoisting motor, a load controlled stopping switch, and means comprising a cam to time the operation of said switch during movement of the car only in a pre-determined maximum coasting zone related to a pre-determined landing.

19. In an elevator system, the combination with the car, a hoisting motor, a load con-

- trolled stopping switch, and means comprising a cam fixed in the elevator hatchway to time the operation of said switch during movement of the car.
- 5 20. In an elevator system, the combination with the car, a hoisting motor, a switch to control stopping of the car, adjustable independently of movement of the car as caused by stretch and contraction of the hoisting cables, 10 and means operable by movement of the car to time the operation of said switch.
21. In an elevator system, the combination with the car, a hoisting motor, a switch to control stopping of the car, means comprising a cam operable by movement of the car only through a pre-determined maximum coasting zone related to a pre-determined landing, to time the operation of said switch, and means to adjust said switch automatically 20 in accordance with the load to vary with respect to the position of the car within said zone, the point at which said switch is open-circuited to discontinue the hoisting operation, so that the car regardless of load capacity will coast in either direction to a gravity stop substantially level with the landing without liability of over-running said landing.
22. In an elevator system, the combination with the car, a hoisting motor, a load controlled switch on the car automatically to control the stopping of said motor, and a cam to time the operation of said switch and having a maximum timing operation proportional 35 to a maximum coasting distance of the car.
23. In an elevator system, the combination with the car, a hoisting motor, circuit-controlling mechanism automatically to control the stopping of said motor, a cam to time the operation of said switch and having a maximum timing operation proportional to a maximum coasting distance of the car, and means controlled automatically by the load with 40 respect to the position of the car relative to said cam, to vary the point at which said circuit-controlling mechanism is open-circuited to discontinue the hoisting operation, so that the car will, regardless of the capacity of 45 its load, coast in either direction to a gravity stop substantially level with the landing without liability of over-running said landing.
24. In an elevator system, the combination with the car, a hoisting motor, a switch automatically to control the stopping of said motor, a cam to time the operation of said switch, and means controlled by the load independently of movement of the car as caused by 50 stretch and contraction of the hoisting cables, to vary the point at which said switch is opened to discontinue the hoisting operation, so that the car will regardless of stretch and 55 contraction of the hoisting cables, coast to a gravity stop substantially level with the land-
- ing without liability of over-running said landing.
25. In an elevator system, the combination with the car, a hoisting motor, circuit controlling mechanism, means adjustable automatically by the load to vary the point at which said circuit-controlling mechanism is open-circuited to discontinue the hoisting operation, so that the car will come to a gravity stop substantially level with the landing 70 by coasting variable distances as dependent on car load and direction of car travel, and means automatically to exactly level the car if subsequently to completing its full coast the car is not at such an exact level with the landing, said leveling means operating automatically to maintain the car at such an exact level during loading and unloading.
26. In an elevator system, the combination with the car, a hoisting motor, automatic 85 means to level the car with a landing, and means to permit time periods of different duration to elapse to permit the car fully to complete coasting as dependent upon load and direction of car travel, such complete 90 coasting bringing the car to a substantial level with the landing and within the bounds of an exact leveling zone before said automatic leveling means is effective to control the car.
27. In an elevator system, the combination with the car, a hoisting motor, automatic means to level the car exactly with a landing, and means operable automatically to introduce time periods of different duration to 100 permit the car to fully complete its coast and come to a gravity stop within the bounds of a predetermined zone corresponding to an substantial level with the landing and without liability of over-running said landing, 105 before said automatic leveling means is rendered effective to take up the control of the car.
28. In an elevator system, the combination with the car, a hoisting motor, a car switch 110 to control operation of the hoisting motor, a stopping switch adjustable automatically in accordance with the load, a cam to time the operation of said stopping switch, and electro-responsive means operable by moving 115 said car switch from "on" to "off" position to render said timing switch operable to co-act with said cam.
29. In an elevator system, the combination with the car, a hoisting motor, a car switch 120 to control operation of the hoisting motor, a stopping switch adjustable automatically in accordance with the load, a cam proportional in length only to the maximum coasting distance of the car, and electro-responsive 125 means operable by moving said car switch from "on" to "off" position to render said stopping switch operable to co-act with said cam.
30. In an elevator system, the combination 130

with the car, a hoisting motor, means to initiate start of the car, a switch automatically to continue movement of the car, and means controlled by the load independently of movement of the car as caused by stretch and contraction of the hoisting cables to control said switch to open to discontinue the hoisting operation at varying points relatively to

any pre-determined landing, so that the car by coasting will come to a gravity stop substantially level with the landing without liability of over-running said landing. ¹⁰

In testimony whereof, I have signed my name to this specification.

ERNEST L. GALE.
